UNITED STATES PATENT OFFICE.

WILLIAM H. LOGAN, OF LOUISVILLE, KENTUCKY, ASSIGNOR TO THE KIRKER-BENDER FIRE ESCAPE COMPANY, OF SAME PLACE.

FIRE-ESCAPE.

SPECIFICATION forming part of Letters Patent No. 623,796, dated April 25, 1899.

Application filed September 7, 1898. Serial No. 690,423. (No model.)

To all whom it may concern:

Be it known that I, WILLIAM H. LOGAN, of Louisville, in the county of Jefferson and State of Kentucky, have invented certain new and useful Improvements in Fire-Escapes; and I do hereby declare that the following is a full, clear, and exact description of the invention, which will enable others skilled in the art to which it appertains to make and use the same, reference being had to the accompanying drawings, and to the numerals of reference marked thereon, which form part of this specification.

My invention relates generally to fire-escapes, and more particularly to that class of fire-escapes which consist, primarily, of a spiral way or slide supported around a central post and inclosed within a vertical cylinder or column.

The object of my invention is to generally improve the construction and operation of this class of fire-escapes; and with this object in view my invention consists in the improved construction, arrangement, and combination of parts hereinafter fully described, and afterward specifically pointed out in the appended claims.

In the accompanying drawings, Figure 1 is a perspective sectional view of part of a fire-escape constructed in accordance with my invention, all the parts being broken away to more clearly illustrate their construction. Fig. 2 is a fragmentary detail perspective view of part of the spiral way, illustrating specially the overlap of the plates of the spiral way and the head on their inner ends. Fig. 3 is a horizontal sectional view taken on the dotted line 3 3 of Fig. 1, looking downward. Fig. 4 is an exterior view in elevation of the double doors, the spring foot-plate and latch being shown in dotted outline.

Like numerals of reference mark the same parts wherever they occur in the several figures of the drawings.

Referring to the drawings by numerals, 10 indicates a vertical cylinder, column, or tower, which may be erected in a building or outside thereof and adjacent thereto in any suitable manner, access being had to the interior there- 50 of at the top or at suitable intervals by any known approved means, the construction of

the tower or the means of access to its interior forming no part of the present invention. In the interior of the tower is erected a spiral slideway, composed of metal sheets or plates 55 11, whose outer edges rest against the inner surface of the tower and may be secured thereto in any suitable manner. The lower edge of each sheet overlaps the upper edge of the next lower sheet, as at 12, and the 60 overlapped edges may be secured together by any suitable means which will leave a smooth surface over which to slide without danger of injury to the person. The inner edge of each sheet is bent to form a bead, as at 13, the 65 bead of each sheet resting upon and slightly overlapping the bead of the next lower sheet, if desired, the beads of all the sheets of a complete slideway forming a central post around which the slideway is arranged, the slideway 70 ending at the bottom at 14, Fig. 3, adjacent to double doors 15 16.

The doors 15 16 are hinged at 17 to open outward, the meeting edge of door 15 overlapping the edge of door 16. Upon the door 75 15, on the inside, are lugs 18 and 19, a vertical latch-bolt 20 being arranged to slide in lug 19 and at its lower end to engage a fixed part of the tower. In the lug 18 is pivoted at its angle an elbow-shaped foot-lever 21, the short 80 arm of which is pivotally connected to the upper end of the latch-bolt 20, while its long arm extends downward in the path of the feet of a person sliding down the way.

22 indicates a spring-plate secured at its 85 upper end by rivets or bolts 23 to the interior of door 15 above the latch. This spring-plate extends downward, overhanging the latch mechanism, the elbow-lever 21 being slidably mounted in a lug 24 on the under side of the 90 spring-plate. The normal tendency of the spring-plate is to force the lower end of the long arm of the elbow-lever outward, thus forcing the end of the short arm downward, carrying the latch-bolt downward with a yielding pressure, thereby making of it a spring-latch bolt to automatically lock the doors when closed. When a person descending in the slideway reaches this point, his feet will come into contact with the spring-plate 22, 95 and depressing said plate will withdraw the latch-bolt and force the doors open without 100

the necessity of raising or manipulating them by hand, thus affording free egress from the tower.

It will be observed that the spring-plate 22 is widened at its lower end, (see dotted lines, Fig. 4,) so that it would be almost impossible for the descending person to miss striking it, and, further, that it performs the double function of spring for the latch and foot-plate for releasing the latch.

The lowermost sheet of the slideway is properly formed to shape the way to end at the spring foot-plate and may be turned up to form a flange on its end line 14, before referred to.

The construction of my invention will be readily understood from the foregoing description and needs no further elucidation. The person descending the tower on the slideway 20 will automatically open the doors at the bottom, and thus cannot by any accident be shut in.

Having thus fully described my invention, what I claim as new, and desire to secure by 25 Letters Patent of the United States, is—

1. A fire-escape comprising a suitable tower, and a spiral slideway therein composed of plates overlapping at their upper and lower edges and connected together at their inner 30 edges to form a central post, substantially as described.

2. A fire-escape comprising a suitable tower and a spiral slideway therein composed of plates united at the upper and lower edges 35 and bent at their inner edges to form tubular beads which join each other and form a complete central, hollow post, substantially as described.

3. A fire-escape comprising a suitable tower and a spiral slideway therein, in combination 40 with double doors in the tower at the foot of the slideway hinged to open outward, a latch-bolt on the inside of the doors, and a latch-lever therefor arranged in the path of the person descending the slideway, substantially as 45 described.

4. A fire-escape comprising a suitable tower and a spiral slideway therein, in combination with suitable doors in the tower at the foot of the slideway hinged to open outward, a latch-bolt on the inside of the door, a spring-plate 50 secured on the door and overhanging the latch, and an elbow-latch lever connected pivotally with the latch-bolt and slidably with the spring-plate, substantially as described. 55

5. The combination with the tower and slideway of the double doors in the tower opening outward at the foot of the slideway, the lugs on the inside of one of the doors, the latch-bolt slidably mounted in the lower lug, 60 the spring-plate secured to the inner face of the door, the lug on the face of the spring-plate, and the elbow-latch lever pivotally mounted at its angle in the upper lug of the door having its inner shorter arms pivotally 65 connected to the latch-bolt, and its depending longer arm slidably mounted in the lug on the spring-plate, substantially as described.

In testimony that I claim the foregoing as my own I affix my signature in presence of 70 two witnesses.

WILLIAM H. LOGAN.
